REFRIGERATOR CABINET CONSTRUCTION

Theodore W. Rundell, Abington, Pa., assignor to
 Philco Corporation, Philadelphia, Pa., a corporation of Pennsylvania

Application February 6, 1948, Serial No. 6,760

7 Claims. (Cl. 62—116)

1

The present invention is concerned with new and useful improvements in cabinet structures, and relates especially to refrigerator cabinets and to outer shell structures therefor.

Broadly, it is an object of the invention to provide an improved wall panel for such outer shells, and to simplify the construction of refrigerators. More particularly, the invention has as an object the provision of a one-piece unitary rear panel member, adapted to extend the full height of the refrigerator cabinet, and so configured as to have an unusually high degree of strength and rigidity.

To these general ends, the invention contemplates provision of a cabinet including a wall member, or panel, which comprises spaced recessed portions, which portions are drawn from the plane of a single unitary sheet in such manner as to leave substantially coplanar marginal flange portions extending about the periphery of the panel and laterally thereof between said spaced recessed portions. One of the recessed portions is provided with an aperture—in a position such as to be upwardly presented when the panel is in use—in order that said portion may serve as a flue promoting flow of cooling air across the refrigerator condenser and providing space within which the condenser may be disposed.

It is an important feature of the construction that the aforesaid recessed panel portions not only effect a very substantial increase in the strength and rigidity of the outer shell assembly, as indicated above, but further make it possible both to utilize insulation of greater thickness and to increase the size of the cabinet inner liner member, if such should be desired, without necessitating an overall redesign of the outer shell. As will be appreciated, fabrication of the U-shaped sheet which commonly comprises the side walls and top of the outer shell involves equipment of considerable cost and complexity, and it will therefore be evident that it is highly desirable to increase the "flexibility" of the cabinet design, without necessitating costly retooling.

A further object of the invention resides in the provision of a panel member of the aforesaid type, which is of such a nature as considerably to facilitate the mounting and support of sound-deadening insulation provided in the machine compartments of refrigerators.

It is an additional feature of the invention that the panel member is of such a nature as to make it possible to manufacture the same by a simple stamping procedure.

The foregoing and other objects and advan-

2

tages of the invention are hereafter set forth, and described and illustrated in the accompanying drawings, in which:

Figure 1 is a view, in perspective, of the rear portion of a refrigerator cabinet incorporating the present invention; and,

Figure 2 is a fragmentary vertical sectional view of the cabinet structure illustrated in Figure 1.

Now making more particular reference to the preferred embodiment illustrated and described, the cabinet structure comprises an outer shell 10 and an inner shell or liner member 11 disposed within said outer shell and defining a storage compartment designated, generally, at 12. Insulation 13 which, for the purpose of the present invention may be of any desired type, fills the space between said inner and outer shells, it being understood that the face portion of the refrigerator is provided with an access opening (not shown) and that the space between the forward marginal edges of the inner and outer shells would be bridged by a breaker strip of low thermal conductivity.

In particular accordance with the present invention, the outer shell 10 is provided with a one-piece, unitary rear panel 14 which extends the full length of the cabinet and includes upper and lower recessed portions shown at 15 and 16, respectively, which recessed portions are drawn from the plane of the sheet during a stamping operation leaving substantially coplanar marginal flange portions 17, extending about the periphery of the panel 14 and also laterally of the panel between said upper and lower recessed portions 16 and 17.

As clearly appears in Figure 2, the upper recessed panel portion is in registry with inner liner 11, while the lower portion 16 serves as the rear wall for a machinery compartment 18 housing a conventional condensing unit, represented at 19. To promote stability of the cabinet structure, it is desirable that the condensing unit be mounted well toward the rear of the machinery compartment 18, and it will be observed that the recessed portion 16 accommodates at least a part of the condenser 20, thereby making it possible to mount the condensing unit further toward the rear of the cabinet than is feasible with many cabinet structures of prior practice.

The upper edge of panel portion 16 is apertured, as shown at 21, in order that said portion 16 may serve as a flue for condenser 20, it being a feature of the invention that the apparatus obviates the necessity of separate fabri-

cation and assembly procedures required when the flue structure is formed as a separate entity.

As indicated at 22, tabs extend from the wall structure defining the opening 21 into the apertured area, which tabs may be turned downwardly, to the position indicated at 23, and thus provide support for suitable sound-insulating material 24.

It is to be noted that in addition to the rigidity inherent in the construction, and the unitary flue structure provided thereby, use of a rear panel construction in accordance with the invention makes it possible to increase the depth of the inner liner 11 without sacrifice of the desired thickness of insulation in the rear portion of the cabinet. As mentioned, supra, this feature makes possible a wider variation in cabinet design, without in any way affecting the tools required for fabrication of the side and top walls of the outer shell 10.

As shown at 25, the rearwardly presented marginal edges of the outer shell 10 are provided with inturned flanging, and assembly of the rear panel with the outer shell member is accomplished by introducing the panel member from the bottom of the outer shell—with the panel flange portions 17 lying behind flanging 25—and then moving said panel upwardly to the position shown in the drawings. As will be understood, the cooperating flange portion 17 and 25 may be secured in face-to-face relation in any suitable manner as, for example, by welding. Introduction of the floor member illustrated at 26, and application of the insulation 13, may then be carried out in accordance with known techniques.

The lower portion of the cabinet is provided with a sill rail 27 which, as is illustrated at 28, is L-shaped in cross section, its upwardly extending flange being secured to rear panel portion 16 and to the side walls of outer shell 10, and its horizontally extending flange portion providing the cabinet base.

From the foregoing description, it will now be understood that the present invention provides a novel and improved refrigerator cabinet structure, which has an unusually high degree of strength and which is so configured as to present—in a single unitary panel structure—both a refrigerator rear wall and a simple and inexpensive flue structure.

I claim:

1. In a refrigerator, a cabinet having a plurality of compartments therein, one of said compartments being adapted to house a condensing unit, and a panel structure associated with a side of said cabinet, said panel structure including a sheet having a recessed portion extending outwardly of the cabinet and having marginal portions secured to adjacent portions of said cabinet, and said recessed portion being so positioned as to comprise wall structure for the said one compartment and being apertured in an upper region thereof, whereby said recessed portion comprises a flue adapted to promote flow of cooling air in heat exchange relation with a condensing unit disposed within said one compartment.

2. In a refrigerator, a cabinet having a plurality of compartments therein, one of said compartments being adapted to house a condensing unit, and a unitary one-piece panel forming a side of said cabinet, said panel having a recessed portion extending outwardly of the cabinet and having marginal portions secured to adjacent portions of said cabinet, and said recessed portion being so disposed as to comprise at least one wall of the

said one compartment and being apertured in an upper region thereof, whereby said recessed portion comprises a flue adapted to promote flow of cooling air in heat exchange relation with a condensing unit disposed within said one compartment.

3. A construction in accordance with claim 1, and in which the edges which define the aperture are provided with displaceable retaining means positioned to support sound-insulating material disposed within said one compartment.

4. In a refrigerator, a cabinet having a plurality of compartments therein, one of said compartments being adapted to house a condensing unit, and a panel structure associated with a side of said cabinet, said panel structure including a sheet having a plurality of spaced recessed portions extending outwardly of the cabinet and marginal flanging extending about at least the major portion of the periphery of said sheet, said flanging being secured to adjacent portions of said cabinet, each of said recessed portions being disposed in registry with a corresponding one of said compartments, and one of said recessed portions comprising wall structure for the aforesaid one compartment and being apertured in an upper region thereof, whereby said one recessed portion comprises a flue adapted to promote flow of cooling air in heat exchange relation with a condensing unit disposed within the said one compartment.

5. In a refrigerator, an outer shell, an inner liner disposed within said outer shell and defining a storage compartment, a machinery compartment disposed within said outer shell in adjacency to said storage compartment, and a unitary one-piece panel forming a side of said outer shell, said panel having a plurality of spaced recessed portions and marginal flanging extending about at least the major portion of the periphery of said panel, said flanging being secured to adjacent portions of said cabinet, each of said recessed portions being in substantial registry with a corresponding one of said compartments, and one of said recessed portions being positioned to serve as a wall of the machinery compartment and being apertured in an upper region thereof, whereby said one recessed portion comprises a flue adapted to promote flow of cooling air in heat exchange relation with a condensing unit disposed within said machinery compartment.

6. For refrigerator cabinet construction, a rigid wall member comprising a panel having spaced recessed portions and flange portions extending about at least a major portion of the periphery of said panel and laterally thereof between said spaced recessed portions, said flange portions being adapted for securing to a refrigerator cabinet, and one of said recessed portions being provided with an aperture—in a position such as to be disposed in an upper section of said one recessed portion when the panel is in use—whereby said one recessed portion may serve as a refrigerator flue structure.

7. For refrigerator cabinet construction, a rigid wall member comprising a pair of shallow pan-like portions and flange portions extending about the free edges of said pan-like portions, said flange portions being adapted for securing to a refrigerator cabinet, and one of said pan-like portions being of such size and shape as to be adapted to comprise one wall of a refrigerator machinery compartment, said one pan-like portion being so configured that said portion

5

may serve as a flue when the panel is associated
with a refrigerator cabinet.
